SPIKE PULLER

Application filed May 26, 1931. Serial No. 540,110.

This invention relates to spike pullers, and more particularly to devices of that type adapted to pull railroad spikes.

An object of the invention is to improve the construction of spike pullers so as to facilitate the engagement of the spike-head-engaging toe of the lever bar with the spike and to enable the spike to be withdrawn completely from the tie without the necessity of placing a block under the foot of the spike puller after the spike has been partially withdrawn in order to raise the foot high enough to complete the withdrawal of the spike.

Another object of the invention is to provide a spike puller in which the claw which holds the spike head in engagement with the lever bar toe is mounted so that it may be swung back and remain in such position out of the way, while the toe is moved into engagement with the head of the spike.

Two forms of construction are illustrated, by way of example, in the accompanying drawings, wherein:

Fig. 1 is a vertical section through the lower part of the spike puller and adjacent parts of a rail and tie, with the puller in engagement with the head of a spike preparatory to withdrawing the latter;

Fig. 2 is a similar view to Fig. 1 showing the spike partially withdrawn;

Fig. 3 is a similar view to Figs. 1 and 2 showing the spike fully withdrawn;

Fig. 4 is a plan view with the lever in the position shown in Fig. 1, but showing the claw in the position shown by dotted lines in Fig. 1;

Fig. 5 is a view similar to Fig. 2, but showing a modified form of spike puller; and

Fig. 6 is a plan view of the parts shown in Fig. 5.

The spike puller shown in Figs. 1 to 4, inclusive, comprises a lever bar having three main parts, a handle 10, foot 11 and toe 12.

The toe is forked so that it may be extended under the head of the spike 13 on both sides, as shown. To hold the toe in engagement with the head of the spike for heavy work, a claw 14 is provided having a downwardly curved end or toe 15 adapted to engage the

opposite side of the spike head. This claw is mounted in a slot 16 in the foot 11 and is pivotally held therein by a pin 17. The inner face of the toe 15 extends downwardly at substantially right angles to the line 55 extending from the pivotal axis of the claw to the end of the toe thereof. In other words, the angle α , α , α of Fig. 1 is preferably about a right angle. This angular relationship is desirable to permit the toe of 60 the claw to be moved into engagement with the head of the spike and when it is in engagement with the spike head to retain it so.

So constructed, the toe of the claw engages the side of the spike-head and not its under 65 side. This construction has very important advantages. First, the claw may be brought into operation before the spike-head has been lifted away from the rail, as shown for example in Fig. 1. Second, as the spike is 70 pulled there is no tendency for the claw to turn the spike-head toward the lever bar and in so doing bend the shank of the spike.

It will be noted that, by virtue of the angular relationship above mentioned, the inner face of the claw-end from the tip thereof upwardly for a substantial distance does not depart widely from the arc described by the back of the spike-head as the latter pivots about the toe of the lever bar. This construction allows the back of the spike-head to slide down the inner face of the claw-end as the angle between the shank of the spike and the foot of the lever bar becomes smaller and smaller. If instead of, or simultaneously with, a sliding movement of the spike-head on the inner face of the claw-end, the claw turns about its pivot, the combined movement of the claw-end and the lever bar toe relatively to each other and to the spike tends to turn the spike-head away from the lever bar and thus counteracts the normal tendency of the spike puller to bend the spike towards itself.

While the toe 12 is being slipped under the head of the spike it is convenient to have the claw out of the way. Further, if the spike is not too firmly embedded in the tie, it may be extracted by the toe 12 without aid from the claw. For these reasons, the 100

slot 16 is extended rearwardly towards the handle 10 so that the claw may be swung back into the position shown in dotted lines in Fig. 1 and by full lines in Fig. 4, to bring its center of gravity to the rearward side of a line drawn vertically upward from the axis about which such claw turns when the underside of the toe 12 is horizontal. After the toe 12 has been slipped under the head of the spike, the claw may be swung forward into the position shown in full lines in Fig. 1.

The foot 11 is formed with a convexly curved bottom face to serve as a rolling fulcrum. This face is to advantage formed with two heel portions 18 and 19 of smaller radius of curvature than the portions between the tip of the toe 12 and the heel 18 and between the heels 18 and 19. The first heel 18 serves as a rolling fulcrum during the initial loosening and withdrawal operations, as shown in Figs. 1 and 2. The second heel 19 serves as a fulcrum during the latter part of the withdrawal operations.

As the distance from the tip of the toe 12 to the heel 18 is short, good leverage is obtained for loosening the spike. The portion of the under face of the toe 12 and foot 11 forward of the heel 18 is approximately at right angles to the handle 10, so as to bring the latter into vertical or nearly vertical position when the toe 12 is slipped under the head of the spike. The under face of the foot between the heels 18 and 19 has a general direction of about 45° with respect to the handle so that, when the foot is properly proportioned to the length of the spike, the latter may be completely withdrawn before the handle in its downward movement touches the ground or the opposite rail.

The distance from the second heel 19 to the tip of the lever bar toe is considerably greater than the length of a standard railroad spike so that when the latter is completely withdrawn, as shown in Fig. 3, the angle between the horizontal and the line joining the tip of the toe 12 and the fulcrum point 19 is around 45° . If this angle were much greater than 45° , the last part of the withdrawal operation would require an excessive movement of the handle, due to the fact that with higher angles a given angular movement of the handle would produce only a relatively small vertical movement of the tip of the toe 12. If this angle were much less than 45° , the heel 19 would be so far from the spike that the leverage would be small. When the angle is about 45° , the distance between the tip of the toe and the heel 19 is best about one and one-half times the length of the spike.

The foot 11 is wider and deeper than the handle 12 to give the requisite strength at the point where the strain is greatest and offset the weakening effect of the slot 16.

The form of construction shown in Figs. 5 and 6 is the same as that shown in Figs. 1 to 4, inclusive, except for the form of the toe of the lever bar and the length of the slot for the claw. In Figs. 1 to 4, the toe 12 is forked. In Figs. 5 and 6, the toe 12a has a straight chisel-edge tip.

It will be understood that numerous changes may be made in the constructions illustrated without departing from the principles of the invention.

What is claimed is:

1. A spike puller, comprising a lever bar having a foot-end extending at an angle to the handle, formed with a convexly curved bottom face to serve as a rolling fulcrum and terminating in a spike-head-engaging toe, and a pivoted claw member mounted on the foot-end and free to swing sufficiently far to the rear to bring its center of gravity to the rearward side of a line drawn vertically upwards from the axis about which such member turns when the underside of the lever bar toe is horizontal, said claw member extending forwardly and curved downwardly and ending in a spike-head-engaging toe.

2. A spike puller, comprising a lever bar having a foot-end extending at an angle to the bar formed with a convexly curved bottom face adapted to serve as a rolling fulcrum and terminating in a spike-head-engaging toe, a claw member pivotally mounted in a slot in the foot-end, the slot extending sufficiently far to the rear to allow the claw member to be moved into such position that its center of gravity is on the rearward side of a line drawn vertically from the axis about which such member turns when the underside of the lever bar toe is horizontal, said claw member extending forwardly and curved downwardly and ending in a spike-head-engaging toe the inner face of which extends downwardly at about a right angle to a line extending from the pivotal axis of such member to the end of the toe thereof.

3. A spike puller, comprising a lever bar having a foot-end extending at an angle to the handle formed with a convexly curved bottom face to serve as a rolling fulcrum and terminating in a spike-head-engaging toe, the fulcrum face having two heel portions with curvatures of shorter radius than the parts of the face between the toe and the first heel portion and between the first and second heel portions, the distance between the tip of the toe and the first heel portion being approximately half the length of a standard railroad spike and the distance between the tip of the toe and the second heel portion being substantially greater than the length of such spike.

4. A spike puller as in claim 3, in which the part of the face between the toe and the first heel has a general direction of 90° to the handle and the part of the face between

the two heels has a general direction of 45° to the handle.

5. A spike puller, comprising a lever bar having a foot-end extending at an angle to the bar formed with a convexly curved bottom face to serve as a rolling fulcrum and terminating in a spike-head-engaging toe, the fulcrum face having but slight curvature for a substantial distance from the toe 10 and then having a curvature of short radius and extending from such part of short radius to a heel point at a distance from the toe substantially greater than the length of the spike to be pulled, and a pivoted claw 15 member pivoted to the lever foot about midway of the length of the foot and near its fulcrum edge and extending forwardly and curved downwardly and ending in a spike-head-engaging toe the inner face of which 20 extends downwardly at substantially right angles to a radius from the pivotal axis of such member to the end of the toe thereof.

In testimony whereof we have hereunto set our hands.
